UNITED STATES PATENT OFFICE.

EDWARD E. PERSHALL, OF ST. LOUIS, MISSOURI.

METHOD OF DISTILLATION.

1,341,437.

Specification of Letters Patent. Patented May 25, 1920.

Application filed February 20, 1918. Serial No. 218,247.

To all whom it may concern:

Be it known that I, EDWARD E. PERSHALL, a citizen of the United States, and a resident of St. Louis, in the State of Missouri, 5 have invented certain new and useful Improvements in Methods of Distillation, of which the following is a specification.

My invention relates broadly to the distillation of hydrocarbon materials. More specifically it relates to the distillation of hydrocarbon pitches and tars so as to obtain a residue of coke. Its primary object is to obtain a relatively high percentage of distillates, and especially a relatively high 15 percentage of the high-boiling, high specific gravity distillates, which are the most valuable elements of the materials enumerated, and to obtain such latter distillates having distinctive properties in that they are substantially unchanged from their natural condition; and also to obtain a superior quality 20 of coke. A specific object is to obtain substantially complete fractionation of distillates whereby substantially the highest percentage 25 of the valuable heavy oils is obtained in the proportions in which they existed in the hydrocarbon mass before distillation was begun, and a residuum of coke which is substantially the smallest quantity 30 obtainable, which is substantially free of all volatile bituminous compounds, which is notably high in fixed carbon, and which, when burned, leaves but a small percentage of ash. A further specific object is to effect substantially 35 complete distillation with substantially a minimum of temperature and quantity of heat, thus effecting a notable saving in fuel as well as reducing the hitherto abnormal deterioration of the apparatus employed due to excessive heat.

Other objects and advantages of the present improvements will appear at various places hereinafter.

By fractionation of the distillates, or fractional distillation, I mean the passing over of the vapors of volatilization according to the specific gravities and boiling points of the several products when condensed, one after the other in the natural order, without 45 the substantial destruction of these several vapors after having been formed. This term is distinguished from "destructive distillation," which comprises the decomposition or "cracking" of the vapors, and which re-

sults first, from the impingement of the vapors upon a surface heated greatly beyond the temperature at which the vapors were formed, and, secondly, from the condensation of the vapors and the falling back of the liquid upon the highly heated surface 60 of the mass, such vapors or liquid thereupon decomposing partially into lighter and partially into heavier substances.

In one aspect of my invention the hydrocarbon material subjected to complete distillation according to the present method and apparatus is pitch, of various consistencies, which pitch may be the product of the partial distillation of coal-gas tar, water-gas tar, coke-oven tar, blast furnace tar, 70 wood tar, or any other similar material. In another aspect the invention is directed to the complete distillation of such tars into and through the pitch state to coke as one continuous operation.

These improvements will be explained in connection with the accompanying drawings, which form a part hereof, and which illustrate a preferred form of apparatus in connection with which my improved method 80 may be carried out. The method is not limited, however, to this particular form of device. The objects and advantages of the present form of still are largely in its provision of substantial uniformity of heat distribution throughout the mass, the saving of fuel, the employment of relatively low temperatures, the avoidance of "cracking" or decomposition, the avoidance of excessive deterioration of the apparatus itself, ease 85 and safety of operation, rapidity of operation, and, generally, in saving cost while obtaining the most valuable distillates in relatively large quantities.

The apparatus illustrated includes an internally and externally fired still. Preferably at least two flues for the heat pass longitudinally through the interior of the still, where the still is of the shape and proportions shown, and which, in my practice, 100 has such capacity as to contain a working charge of approximately eight thousand gallons of tar. For a still of greater capacity the number or size of such flues may be increased, and in a relatively small still a single flue will suffice. The desideratum in this respect is to provide such heating surfaces that all portions of the mass are fairly

equally subjected to the distilling heat, or, in other words, substantially to equalize the transmission of heat throughout the mass. In my practice the tubular retort is approximately fifteen feet long and ten and one-half feet in diameter, and the two flues are respectively two feet in diameter, and they extend from end to end of the retort. Their arrangement to provide the desired heating result and also access for cleaning out the residuum is well illustrated in the drawings, which are substantially true to scale. Steam is admitted preferably at the bottom and distributed in fine jets from end to end of the retort. A condensing system is provided for the vapors of distillation, which system and the interior of the retort are preferably under a partial vacuum of various degrees of intensity, according to the amount of steam employed or the rate of volatilization, or both. Collecting tanks, preferably several of them for convenience of operation, are also employed, with suitable pipe connections, and also means for providing distilling heat. The upper portions of the retort are not in contact with the heating gases or flame.

In the present form of still decomposition or "cracking" of the vapors of distillation is avoided by maintaining the upper surfaces of the retort at a medium temperature, and particularly one not greater than that at which the distillation is taking place; and, in obtaining the notable advantages of fractional distillation of the heavier oils, such maintenance of a medium temperature is particularly important during the latter stages when these heavier oils are passing over. At the same time condensation of the vapors is substantially avoided through the maintenance of the upper portions of the still at such medium temperature; and, where the temperature of the upper portions of the still may be materially below that at which the vapors are being formed condensation is materially avoided through the employment of steam introduced into the retort and mixing with the vapors of volatilization, and, as a further means for avoiding or reducing the condensation, rapidly drawing away the combined oil vapors and steam through suction in the discharge pipe leading from the retort.

It is not broadly new at this time to produce coke from the complete distillation of tar, the same having been done in Europe as early I believe as the middle of the nineteenth century. It is also old to employ steam or vacuum, and steam with vacuum, in a retort during the process of such partial distillation as results in a residue of ordinary pitches; but I claim it as new to employ steam, with or without vacuum, at the time when the formation and deposition of coke or heavy residues on the bottom and

sides of the retort would otherwise take place in substantially large quantities, and in continuing the use of steam until the complete formation and final hardening of the coke, thus saving the retort from destructive overheating and gaining the further advantages herein above and hereinafter pointed out. It is also new to heat the mass by internal and external application, and to provide for the continued flow or movement of the mass over and about the heated surfaces of the retort until final hardening takes place. It is also novel in such complete distillation to maintain the upper surfaces of the retort at a medium temperature to avoid cracking, and to employ steam, with or without vacuum, in connection with such medium temperature of said upper surfaces. Still other features of novelty will appear from this description and in the appended claims.

The presence of steam applied as herein pointed out from small jets into the body of the hydrocarbon mass substantially up to the time of the formation of coke has several distinct actions upon the mass and upon the vapors of distillation, namely; first, a mechanical one whereby the vapors are carried along by the steam currents to the condensing apparatus; secondly, a solvent action upon the vapors whereby the steam particles act as vehicles in carrying the vapors away, and without changing their composition, and doing so more quickly and certainly than by the mere mechanical action next hereinabove described; thirdly, by creating a system of partial pressures of the vapors of distillation and of the steam, inducing volatilization at a temperature lower than the true boiling point of the hydrocarbons from which the vapors are being produced; fourthly, the creation of currents within the mass, which currents are preferably controlled so as to cause the mass to circulate and thus cooperate in avoiding local overheating or underheating of portions of the mass within the still.

The foregoing four actions of the steam are utilized by me in the partial distillation of the tar down to and including the formation of pitch. Preferably the steam is not used until the lighter oils have passed over, the tendency of the steam being to condense objectionably at the lower temperatures of the still. In obtaining the valuable distillates of the heavier specific gravities and higher boiling points from the pitch and in the production of coke further advantage is taken of these four actions of the steam mentioned, together with other actions which I have discovered to be of great utility and which have an important bearing upon the distillates and coke, as well as upon considerations of safety to the

workmen and to the apparatus employed. These several other actions are as follows:

Fifthly, the carrying away of obnoxious gases arising from the coke in its heated state, similar to the first action mentioned above, and which gases are liable to combustion or which would otherwise be a menace to the workman;

Sixthly, the absorption of such gases, in a manner similar to that of the second action mentioned above;

Seventhly, the distribution of heat;

Eighthly, preventing the coke from adhering tightly or cementitiously to the walls 15 of the retort;

Ninthly, giving the coke a peculiar construction characterized by relatively deep cells in substantially parallel arrangement and having relatively thin walls;

Tenthly, cooling down the mass;

Eleventhly, moistening the mass;

Twelfthly, overcoming the partial vacuum in the retort while continuing the action of the suction creating apparatus, thereby 25 preventing the walls of the retort from collapsing, which might occur under vacuum and high temperature in the last stage;

Thirteenthly, the final filling of the retort with steam so that when opening the 30 same for cleaning and air is admitted there is no danger of an explosion.

In the drawings referred to Figure 1 is a front elevation of the still with a portion of the end wall broken away;

Fig. 2 is an elevation of the condensing and collecting apparatus;

Fig. 3 is a transverse vertical section, as on the line 3—3 of Fig. 6;

Fig. 4 is a greatly enlarged fragmentary 40 sectional view of the steam pipe in its relation to the bottom of the still;

Fig. 5 is a fragmentary transverse vertical section, as on the broken line 5—5 of Fig. 6; and

Fig. 6 is a vertical longitudinal section 45 through the still as on the broken line 6—6 of Fig. 1.

The retort 10 in my practice is of boiler plate, is tubular, and is provided with two flues 11 and 12 from end to end of the retort rigidly and tightly secured to the end walls according to standard practice in boiler making. The retort is suitably supported by brick side walls 14 and 15, a rear wall 16, and a front wall 17. A Dutch oven, which requires no detailed description, is shown at 18, and the front wall 19 spaced from the wall 17 provides a passageway 20 for the burning gases from the oven to the flues 11 and 12 for internal firing. The rear wall 16 is formed to provide a passageway 21 for these gases leading downward to the heating chambers 22, 22^a, defined by the bottom and lower side portions 60 of the retort and by the layer of bricks 23

supported by the bed of ashes or other suitable material 24. The heating current passes into the chamber 22 through arched openings 25 formed in the masonry.

Two oppositely disposed baffle walls 28 70 are provided for preventing the heating currents from playing too strongly proportionately upon the side portions of the retort, or, in other words, the baffles 28 provide a passageway between the chambers 22 and 22^a 75 effectively close to the bottom portions of the still. Thus, while the gases in the chamber 22 will exert heating effect upon the side portions of the retort they are compelled by the baffles 28 to pass substantially under the 80 retort between the two baffles, and since this constricted opening, indicated at 30, Fig. 3, is the shortest and most direct passage-way for the gases entering through the openings 25 the effect is that by far the greater 85 amount of the externally applied heat is directed to the lower portions of the retort.

From the chamber 22^a (Fig. 6) the heating current passes forward and upward into the lateral chambers 32 (Figs. 1 and 5) and 90 thence upward into the transverse chamber 33, and thence into the stack 34 provided with the damper 35.

The retort is provided with two top manholes and covers at 38 and 39. The pipe 40 95 leads to the condensing apparatus from the top of the retort. It is provided with a hand valve 41 and a vacuum safety valve 42. The retort is provided with a safety pressure valve 43.

Steam is admitted through the pipe 45 which terminates near the bottom of the retort midway of the discharge pipe 46, the latter having small lateral openings 47 (Fig. 4) of a combined cross area preferably less 105 than the cross area of the pipe 45 whereby steam will issue from all of the openings 47. The pipe 46 is preferably arranged close to the bottom of the retort 10. The effect of the steam, among other advantages, is to 110 produce currents in the mass substantially as shown by the arrows in Fig. 3, co-operating in equalizing the distribution of heat.

An important feature of the construction is in the relation of the upper portion of the 115 retort 10 to the heating current. It will be noted that the direct application of heat to the exterior walls of the retort is substantially only half-way upward from the bottom. The wall 50 (Fig. 6) protects the upper front end portion of the still from the direct action of the heat, while the wall 51 protects the upper rear end portion against becoming too cold. The upper side and the top surfaces are also bricked over by the 120 wall 52 to protect these surfaces from the cold. The covering walls 51 and 52 have the further and important function of absorbing, conducting and retaining considerable 125 quantities of heat from the still as a whole 130

and thereby maintaining the upper side and top portions of the retort at a medium temperature by which I mean one not hot enough to "crack" the vapors of distillation 5 or cold enough to cause substantial condensation of these vapors when steam is used as herein set forth. The covering walls 51 and 52 are materially thick. Silica bricks are well adapted for such use since the same 10 are high in heat-retaining properties. An asbestos covering 53 over the walls 51 and 52 protects them from the outside temperature while preventing substantial radiation from these walls. It is pointed out that the walls 15 51 and 52 automatically exert their desired influence in this respect during the whole period of distillation since they naturally become hotter as the heat of the still is gradually increased to distil the heavier 20 compounds.

The outlet pipe structure 54 has a substantially large opening into the retort, and pipes 55 and 56 lead from the outlet pipe 54 to the manhole chambers 38^a and 39^a respectively, thus providing for the rapid withdrawal of the vapors from a plurality of places along the top of the retort, centrally as well as nearer the ends. While I prefer a plurality of such withdrawal openings, 30 the same is not strictly necessary.

For removing the coke from the still I provide a manhole and cover therefor shown at 58. A tubular extension or neck leads from the interior of the retort 10 to the man- 35 hole cover through the wall 16.

The condensing apparatus 60 is of the usual form comprising a coil of pipe in a tank of water. Two collecting cylinders 61 and 62 are arranged to take the liquid of 40 condensation from the container, and by means of the pipe 63 the liquid is drawn off as desired. Ordinarily one tank will be used at a given time for receiving the products of distillation, suitable valves as indicated being adapted to shut off one or the other of 45 the tanks as desired. A partial vacuum is created in the tanks 61 or 62, and consequently in the condensing worm 60, in the pipe 40 and in the upper portion of the retort 10, by any suitable means, such, for instance, as the steam siphon 64 connected by 50 a suitable valve-controlled pipe system 65 to the tanks respectively.

My improved method will be described in 55 connection with the complete distillation of refined coal tar to coke, and by refined coal tar I mean a tar produced by the removal of the lighter constituents amounting to approximately 5% of the coal tar in its crude 60 state. The tar is introduced into the retort through any suitable pipe, not shown, or through one of the top manholes illustrated, to a suitable height in the retort dependent upon the water content, the free 65 carbon content, and the amount of coke

which will result from complete distillation. These several properties of the tar are variables and those skilled in the art can readily approximate the proper maximum charge. The minimum charge should be sufficient to cover well the flues 11 and 12. In my practice with the above-mentioned refined coal tar the average maximum charge fills the retort up to seven-eighths of its capacity. 70

Having closed all openings except the pipe leading to the condenser, the fire is started and distillation begins. Partial vacuum is created in the condenser and in the top portion of the still, which vacuum may suitably be equal to about two or three inches of mercury. The process of distillation may well continue with or without the admission of steam until after the major portion of the distillates have been collected. 80 The admission of steam during the earlier stages is sometimes objectionable on account of the excess of water condensed. When, however, the specific gravity of the distillates has reached about 1.15 at a temperature of 100° F. it is to be considered that steam is being admitted in a relatively small quantity, and has as one of its functions the agitation of the mass through the formation of currents therein, which currents are preferably according to predetermined lines. Thus, in the still illustrated the steam issuing laterally from the horizontal pipe 46 causes currents to form upward along the sides of the still and over 90 the tops of the flues 11 and 12 and downward between the flues, the currents thus being substantially around these flues. In my practice during the distillation from time to time I increase slightly the amount of steam admitted, say every half hour, the additional steam acting to continue the currents in the gradually thickening mass. The admission of steam during the passing over of the distillates has the further advantages of creating the system of partial pressures and the carrying away of the vapors of distillation as pointed out hereinabove. 100

The foregoing steps including steam and vacuum are carried on until the final stage 115 of distillation, which is just prior to the time when the coke is beginning to form and swell in the retort. This final stage can be determined by anyone skilled in the art by observing the character of the heavy distillates then being collected. At this time I prefer substantially to discontinue the firing in the oven, and to close the stack damper so as to retain the heat. At this time also the amount of steam admitted is 120 greatly increased. The admission of such considerably larger quantity of steam destroys the vacuum in the retort and places the interior thereof under slight pressure. The action of the vacuum-producing appa- 130

ratus is accelerated so as to limit the steam pressure in the retort to a substantially small amount. It is pointed out that when the coke is actually forming and there is nothing in the retort but substantially dry material the intensity of the heat retained by the brick-work is sufficient to complete the distillation, especially in view of the fact that with an excess of steam the hydrocarbon materials are vaporized at a much lower temperature than without the steam.

In my practice with the refined coal tar mentioned the complete distillation to coke ordinarily consumes from eighteen to twenty hours from the time distillation actually begins. The steam is first admitted after distilling for about twelve hours. A very small fractional turn of the steam valve is made every half hour or so during the next say five hours. Thereupon the coking stage is ordinarily reached, and thereupon the amount of steam admitted is greatly increased, which, in my practice is substantially all that can flow through a one inch pipe valve at say one hundred pounds pressure. It is at this time also that the firing is reduced and the stack damper is closed, and the distillation then proceeds to its completion, which ordinarily consumes say three more hours. The actual time consumed depends upon such considerations as the character of the tar, the intensity of the fire from the oven, the amount of steam and vacuum employed, etc., all as will readily be appreciated and put into practice by those skilled in the art. The actual time consumed for each stage can be accurately determined by the specific gravities of the distillates from time to time.

Assuming the method to have continued as above outlined for say twenty hours, or to complete distillation, the action of the vacuum-producing apparatus is here discontinued, but the admission of steam is continued in full force for a period of from one to six hours thereafter for the purposes of removing all obnoxious gases, cooling down the mass as a whole, moistening the mass, overcoming the tendency of the coke to stick to the walls of the retort, and the removal and dilution of combustible gases to prevent explosion and fires taking place when air is first admitted. The duration of this last mentioned period of from one to six hours is determined by the temperature in the retort, which may be indicated by a pyrometer with which the retort is equipped, but which is not shown in the drawings. Briefly stated, this period will continue until the retort is at a temperature sufficient to warrant the beginning of the cleaning-out operation, say 450° F. At this time the steam is turned entirely off.

The manhole doors 38, 39 and 58 may now

be opened and a draft may be induced, by any approved means, through the top man-hole openings to free the retort of the vapors of steam. At this time the temperature of the mass of coke is still greater than the boiling point of water, which causes it to dry out quite rapidly, and before the interior of the retort is cool enough to admit a workman with comfort the coke is entirely dry. In this connection it is pointed out that the coke will be cooled progressively by the air entering the rear manhole as the workman proceeds with the cleaning-out operations. After the workman has gained entrance to the interior he is supplied with a draft of air through the rear manhole.

An analysis of an average sample of coke made from the above mentioned refined coal tar in the still illustrated and in accordance with the method herein described is as follows:

Moisture .37%; volatile matter 4.78%; fixed carbon 94.42%; ash .43%; B. T. U. 15730; sulfur .7%; water soluble 1.43%.

The distillates which are obtained are almost entirely if not entirely the result of fractional distillation, and are therefore of distinctive character, and substantially the maximum yield of these high-boiling products is obtained.

The high-boiling, high specific gravity distillates are peculiar and distinctive in appearance. They also contain a relatively low percentage of compounds which crystallize, solidify, or settle out at ordinary temperatures. They are furthermore of such distinctive character as to render their subsequent refinement more easy, rapid and satisfactory than in the case of the high-boiling, high specific gravity distillates obtained by methods heretofore known. Owing to their distinctive character, also, it is possible to collect them separately or to segregate them with substantial accuracy, a feature of great advantage in view of the desirability of subjecting certain of them to subsequent treatment.

It is obvious that both the process and apparatus herein described and illustrated may also be employed in distilling pitch of various degrees of consistency. In distilling coal tar pitch of the heavier consistencies, for instance, such as of paving pitch, the flues 11 and 12 located as shown in the drawings would be covered and the retort would be filled to about one-half of its capacity. A pitch of such consistency is obtained in the distillation of crude or refined tar and is reached at about the end of the first ten hours of the complete distillation hereinabove described. Lighter pitches would be obtained earlier and heavier pitches later than the ten hour period mentioned. The above described method, when employed for distilling pitches, would proceed in each in-

stance from that point in the process of complete distillation set forth where a pitch of corresponding consistency is formed.

I claim:

- 5 1. The step in the method for the complete distillation of liquid hydrocarbon material to substantially dry coke, which is the admission of steam within the body of the mass immediately prior to, at and after the
10 change from the substantially plastic state of the mass into the coke state.
2. The method of distilling liquid hydrocarbon material to substantially dry coke which includes heating the mass substantially uniformly throughout, and agitating the mass by currents of live steam from a time prior to the formation of coke until the formation of the coke.
3. The method of distilling liquid hydrocarbon material to substantially dry coke in a substantially closed retort which includes creating a partial vacuum in the retort, heating the mass, and introducing steam thereto in gradually increasing quantities as the mass increases in specific gravity, and introducing a relatively large amount of steam into the mass at about the time the coke is forming.
4. The method of distilling liquid hydrocarbon pitch in a substantially closed retort which includes heating the pitch in the retort, creating a partial vacuum therein during the preliminary stages of distillation, introducing steam into the mass in relatively small quantities during the latter stages of distillation, introducing materially large quantities of steam at about the final stage of distillation, and continuing the introduction of materially large quantities of steam during the complete formation of the coke.
5. The method of distilling hydrocarbon pitch to substantially dry coke which includes the fractional distillation of the volatile elements of the pitch in a still having a heating oven and a retort having masonry walls encompassing a portion thereof, the introduction of steam to the mass during the coking operation, continuing the coking operation by means of the latent heat contained in the structure of the still, and providing a flow of steam through the mass and out of the retort until the retort and mass are substantially cooled.
6. The method of obtaining a high per-

centage of high-boiling, high specific gravity distillates from the complete distillation of hydrocarbon pitch in a substantially closed retort which includes the admission of steam within the body of the mass prior to, at and after the change from the substantially plastic state of the mass into the coke state while maintaining the top portion of the retort at a temperature at which the vapors of distillation will not decompose by contact therewith.

7. The method of obtaining a high percentage of high-boiling, high specific gravity distillates by distilling hydrocarbon pitch to coke which includes heating the pitchy mass substantially uniformly throughout by internal and external firing in a substantially closed retort, and agitating the mass by currents of steam from a time prior to the formation of coke until the formation of the coke.

8. The method of obtaining a high percentage of high-boiling, high specific gravity distillates by distilling hydrocarbon pitch to coke which includes heating the pitchy mass substantially uniformly throughout by internal and external firing in a substantially closed retort, agitating the mass by currents of steam from a time prior to the formation of coke until the formation of the coke, and all the while maintaining the upper portion of the retort at a temperature not higher than that at which the distillates would decompose.

9. The method of obtaining a high percentage of high-boiling, high specific gravity distillates by the complete distillation of coal tar pitch in a substantially closed retort which includes the heating of the pitch in the retort, the creation of a partial vacuum therein during the preliminary stages of distillation, the introduction of live steam in relatively small quantities during the latter stages of distillation, the introduction of materially large quantities of steam at about the final stage of distillation, continuing the introduction of steam during the complete formation of the coke, while maintaining the upper portions of the retort at a temperature at which the distillates will not decompose during substantially all of the period of distillation.

EDWARD E. PERSHALL.
